UNITED STATES PATENT OFFICE.

JOSEPH A. FOXGROVER, OF CHICAGO, ILLINOIS.

BRAKE-BEAM SAFETY BRACKET.

Application filed April 6, 1925. Serial No. 21,225.

My invention relates to railway draft appliances, and in particular to the brake beam assembly of car trucks. Among the objects which the invention has in view are: the provision of a novel and improved form of safety bracket for brake beams; the provision of such a bracket which may be applied to any car truck assembly without withdrawal from service; the provision of such a bracket which is mounted without the use of bolts, rivets, or welding, and which may readily be detached and dismounted.

With these, and such other objects in view as will be apparent from the description, my invention resides in the novel construction, combination and arrangement of parts hereinafter described and claimed, and illustrated in the accompanying drawings, of which:—

Figure 1 is a vertical longitudinal section through a car truck, with parts removed, illustrating the mounting of the safety bracket;

Figure 2, a top plan view thereof, with parts broken away for clearness of detail;

Figure 3, a perspective of the bracket as mounted on a truck channel beam; and

Figure 4 is a fragmentary perspective of a channel beam forming a part of this invention.

The usual construction of railway car trucks employs brakes 10 on the ends of a pair of transverse brake beams 11 supported by pendent bars 12 pivoted in the arch bars 13; the brake beams paralleling the flanges of the channel beam, which beam usually forms the spring plank, or seat.

In the present form, the invention is shown as applied to trucks having a transverse channel beam 14 downturned, with the flanges 15 depending from its sides.

It is a frequent cause of accidents, that the brake beams come loose at their ends, dropping down; so much so that laws have been enacted compelling railroads to equip trucks with some means for preventing the drop of the brake beam, when loosened. My invention is designed to fill this requirement, and in such manner that the trucks need not be withdrawn from service for installation.

In detail, the invention comprises a pair of wide, heavy metal straps 16 laid over the upper face of the channel beam 14 adjacent each end thereof, and having their end portions 17 bent down on opposite sides of the beam and depending below the flanges 15.

Each of the flanges 15 is provided with a

notch 18 cut in its edge, and the depending end portions 17 of the straps are each provided with a vertical slot 19, the tops of which register with the bottoms of the notches cut in the edges of the flanges, so that the slots and notches are in alignment transversely of the beam. The slots 19 extend appreciably below the edge of the beam flanges, and are adapted to receive therethrough a bracket bar 20 which is passed through the slots in the strap ends and is supported thereby transversely of and beneath the beam 14, the length of the bar being such that it projects beyond each side of the beam, considerably under the brake beams 11, forming an efficient support therefore in case of a drop.

By reason of the registry of the top of the slots 19 with the notches 18 in the channel beam flanges, when the bars 20 are inserted in the strap ends, the top of each bar will seat in the flange notches to lock the bracket in position against any movement longitudinally of the channel beam. The bars 20 are secured against any shifting transversely of the channel beam, by means of cotter pins 21 passed therethrough adjacent the outer faces of each of the depending strap ends 17.

In application of the bracket, it is only necessary to cut the notches 18 in the beam flanges at the desired points, which may be done by a blow torch. The straps 16 are then applied over the channel beam to bring the slots thereof in alignment with the notches, and the bracket bars 20 passed through the slots and notches to anchor the bracket in position. The cotter pins are then applied to secure the bars 20 against displacement. It will be noted that no bolts, rivets or welds are employed in the installation of the device and that, it is readily installed and quickly detached when desired, without altering the present structure of trucks, and without necessitating a withdrawal from service.

While in this preferred embodiment of the invention I have illustrated and described certain details and materials entering into the construction and operation thereof, I desire it to be understood that the invention is not limited thereto, but that any desired modifications and changes may be made in the structural details as will fall within the scope of the invention as claimed.

I claim:—

1. A brake beam safety bracket compris-

ing the combination with a channeled truck beam having flanges provided with edge opening notches, of a strap disposed over said beam and having slots therein, and a bracket bar passed through said slots for support in said strap, and seated in said notches for anchoring said strap and bar to the beam.

2. A brake beam safety bracket comprising the combination with a channeled truck beam having notches in the edges of the side flanges thereof, of a strap disposed over said beam and having end portions depending therefrom at each side of said beam, said end portions having slots therein in registry with said notches, and a bracket bar passed through said slots and notches beneath said beam.

3. A brake beam safety bracket comprising the combination with a channeled truck beam having its side flanges notched in transverse alignment, of a strap disposed over said beam and formed with depending end portions at opposite sides thereof, said end portions extending below said beam and

having vertical slots therein for registry with said notches, a bracket bar passed beneath said beam in the slots of said strap end portions and extending from opposite sides of said beam, a portion of said bar being seated in said notches to prevent shifting longitudinally of the beam.

4. A brake beam safety bracket comprising the combination with a channeled truck beam having its side flanges depending and notched in transverse alignment, of a strap disposed over said beam and having depending end portions extending below the sides of said beam, said end portions being vertically slotted beneath the edges of said side flanges and in registry with the notches thereof, a bracket bar passed through all of said slots and notches for support by the ends of said strap below said beam and extending beyond the sides thereof, and means on said bar for preventing shifting thereof transversely of said beam.

In testimony whereof I affix my signature.

JOSEPH A. FOXGROVER.
